United States Patent Office

Des. 225,191
Patented Nov. 28, 1972

225,191

DISPLAY STAND

Andelfo J. Russo, Blauvelt, N.Y., assignor to Cadillac
Wire Corp., Emsford, N.Y.

Filed Mar. 19, 1971, Ser. No. 126,392

Term of patent 14 years

Int. Cl. D6—06

U.S. Cl. D6—28

FIG. 1.

FIG. 2.

FIG. 3.

In the drawings:

FIG. 1 is an exploded perspective view of a display stand embodying my new design;

FIG. 2 is a perspective view of the display stand of FIG. 1 in assembled form; and

FIG. 3 is a perspective view of an alternative embodiment of the base of my display stand, wherein the base is provided with a plurality of panels.

I claim:

The ornamental design for a display stand, as shown and described.
